G. W. TODD,
DISPENSING RECEPTACLE FOR LIQUID ANESTHETICS.
APPLICATION FILED JAN. 26, 1918.

1,272,579.

Patented July 16, 1918.

UNITED STATES PATENT OFFICE.

GEORGE W. TODD, OF OMAHA, NEBRASKA.

DISPENSING-RECEPTACLE FOR LIQUID ANESTHETICS.

1,272,579.

Specification of Letters Patent. Patented July 16, 1918.

Application filed January 26, 1918. Serial No. 213,988.

To all whom it may concern:

Be it known that I, GEORGE W. TODD, a citizen of the United States, residing at Omaha, in the county of Douglas and State 5 of Nebraska, have invented certain new and useful Improvements in Dispensing-Receptacles for Liquid Anesthetics, of which the following is a specification.

This invention relates to a dispensing receptacle for liquid anesthetics, and has for 10 one of its objects to provide a receptacle which will conserve the product effective in producing total or partial insensibility to pain, for use in the practice of dentistry or 15 surgery. Another object is to provide a receptacle for dispensing a liquid anesthetic which may be conveniently held by the person under treatment and may be self-administered to produce semi-consciousness or total 20 insensibility to pain. The invention also has reference to such a construction for the device that the exhalations of the patient will be discharged to the atmosphere instead of mingling with the inhalations, and includes 25 features found to be of advantage for thoroughly breaking up the liquid, also for a control of the proportion of air admitted to the mixture, and for convenient sanitation.

30 With the foregoing objects in view and others to be mentioned hereinafter, the invention presents a novel construction, combination and arrangement of parts as described herein and claimed, and as illustrated in the accompanying drawing, wherein,

Figure 1 is a partly broken view illustrating one embodiment of the invention, being a section on line 1—1 of Fig. 2. Fig. 40 2 is a plan view of the device. Fig. 3 is a transverse section on line 3—3 of Fig. 1. Fig. 4 is a transverse section on line 4—4 of Fig. 1. Fig. 5 shows a modified form for the inhaler. Fig. 6 shows the receptacle 45 provided with an inhaler constructed integral therewith.

Referring now to the drawing, numeral 7 indicates an elongated receptacle having a comparatively large opening 8 in one of its 50 ends, a removable stopper 9 being employed to make a closure thereof, the receptacle, at its opposite end being provided with an exit way or conduit 10 with terminal prongs 11, removable stoppers 12 being employed 55 to make a closure of said conduit.

In Figs. 1, 2 and 3, the conduit is shown

to be removable from the receptacle, the latter being provided with a bushing 13 in which the conduit may be threaded. Fig. 6 illustrates a conduit 10' which is integral 60 with the receptacle, and I may employ either of these constructions since one is the equivalent of the other. Also, while the receptacle and the conduits are preferably constructed of glass, any suitable imperforate material may be used.

Numeral 14 indicates an air intake for the receptacle, this intake being provided with a hollow cylindrical stopper 15 in which is removably mounted a comparatively small stopper 16, and in operation, the stoppers 12 being removed, air may be admitted by removing one of the stoppers 15 or 16, depending upon the volume of air desired for a movement through the receptacle.

Numeral 17 indicates a second elongated receptacle having an open end *a*, its side walls and end *b* preferably being constructed of wire gauze or equivalent material. It 80 is supported in a position adjacent to the bottom of the receptacle 7, in the recesses *c* of the pair of blocks 18 with which the wall of the receptacle 7 is provided, its open end being adjacent to the opening 8. Numeral 85 19 indicates a supply of cotton or similar fibrous material with which the receptacle 17 is partly filled.

At 20, best shown in Fig. 3, is a chamber in communication with the intake 14 and the 90 conduit 10, this chamber being disposed above the receptacle 17 and formed by means of an arcuate hood or transversely curved web 21 of wire gauze, its lower edges being disposed upon the blocks 18; and the space 95 above the foraminous hood 21 and below the receptacle 17 is filled loosely with cotton 22.

It will be understood that an anesthetic liquid when placed in the receptacle 17 will 100 saturate the fibrous element 19 therein, and all of the fibrous parts 22 above the hood and below the receptacle 17 will become saturated to a greater or lesser extent by capillary attraction, this being a desired result so that the gas will become thoroughly mixed with the air within the chamber 20, and in operation, the air while passing through this chamber to the conduit 10, will 105 become charged with the gas, the proportions of air and gas being adjusted by means of the stoppers 15 and 16, and of course,

modified by the movement of air induced by inhalation.

It will be seen that by use of the present invention, the gas may be self-administered, 5 the patient holding the receptacle with the prongs 11 at or within the nostrils, for inhalation, this feature being of importance since the act is self imposed, and the overt act of another in administering an anesthetic 10 generally induces nervousness and mental resistance on the part of a patient. By use of the device, complete insensibility may be attained or a drowsy condition induced, as may be required for the particular surgical 15 or dental operation to be performed, the condition of the patient being such that there will be no sensation of pain during said operation.

At *d* is indicated a frame-member or ring 20 which is secured to the inner side of the receptacle 17, adjacent to the open end thereof, this being for use in connection with a conventional glass container having an attenuated neck and used commercially for 25 holding a liquid anesthetic, and being in general use, requires no explanation, except to state that the liquid product is expansive and the container must be broken to make use of the contents. In the present instance, 30 after the stopper 9 has been removed, the neck of the container mentioned is inserted in the ring *d* for convenient breakage, and the liquid contents will be discharged within the receptacle 17, any particles of glass being disposed upon and held by the cotton 19.

Fig. 5 of the drawing illustrates a modified form for a conduit 10" adapted to have a threaded connection with the receptacle and preferably having a flexible part 40 of funnel-shape adapted to engage the face of the patient, this construction being of advantage in some instances since it permits a more rapid inhalation.

It will be noted that, by use of the device, 45 the exhalations in all instances will be to the atmosphere, this obviously being of advantage. Also there will be no appreciable loss of the product since, when not in use, closures of all ports are made by means of 50 the stoppers mentioned.

In addition to the uses of the device mentioned, it should be stated that it is particularly well adapted for the treatment of catarrhal affections, any of the discharge 55 conduits as shown and described being of advantage for a free delivery of air charged with any one of the various liquid remedies

used for that disease, the construction being such that the air, while moving from the intake 14 to the conduit 10, 10' or 10", will 60 be exposed to the remedial liquids which saturate the fibrous elements 19 and 22.

While I have shown a pair of blocks 18 for a support of the second receptacle 17 and have shown and described a hood 21 of 65 foraminous material, these features are not of importance, but are preferred, since the blocks operate to prevent end thrusts of said receptacle 17 and maintain it in a position adjacent to the bottom of the receptacle 7, and the hood provides an open passageway between the air intake 14 and the discharge conduit.

Having fully described my invention, what I claim and desire to secure by Letters Patent is,—

1. A dispenser for liquid anesthetics consisting of a receptacle having an air intake port, an exit port and an opening in its end, a second receptacle having a foraminous 80 wall and disposed within the first named receptacle, a fibrous element between the walls of said receptacles, a fibrous element in the second receptacle, said last named receptacle having its open end disposed adjacent to the opening in the end of the first named receptacle to permit a deposit therein of a liquid element, and removable closures for the intake and exit ports and opening in the end of the first named receptacle. 90

2. A dispenser for liquid anesthetics consisting of a receptacle having a discharge conduit at one of its ends, its opposite end having an opening formed therein, said receptacle being provided with a port for a 95 movement of air therethrough to said discharge conduit, adjustable means for limiting the movement of air through said air intake port, a removable closure for the opening in the end of said receptacle, a second 100 receptacle having an open end and a foraminous wall, said second receptacle being disposed within the first named receptacle with its open end adjacent to the opening in the end of the first named receptacle, a fibrous 105 element between the walls of said receptacles, and a fibrous element in the second receptacle.

In testimony whereof, I have affixed my signature in presence of two witnesses.

GEORGE W. TODD.
